UNITED STATES PATENT OFFICE

CHESTER A. WEED, OF BROOKLYN, NEW YORK, ASSIGNOR TO THE NATIONAL ACME COMPANY, OF CLEVELAND, OHIO, A CORPORATION OF OHIO

COLLET AND PUSHER

Application filed April 7, 1930. Serial No. 442,298.

This invention relates to collets and pushers particularly adapted for use with metal working machines such as automatic or multiple spindle screw machines and other machines where a device of this kind is used, the object of the invention being to provide an improved collet or pusher inexpensive to manufacture, efficient in use and simple in construction and in which the spring fingers 5 are so formed that they will have the necessary flexibility to enable them effectively to grasp the stock or work without affecting the durability thereof, whereby the cracking, fracture or breaking off or bending of the fingers is prevented.

As is well known the pusher is a device used in connection with a feed tube for pushing a stock bar through a work spindle into position to be operated upon by the tool, 10 while a collet is a device frequently used with a pusher for gripping the stock bar after it has been pushed forward by the pusher and both are commonly made with spring fingers and various attempts have been made for 15 some time past to make a practicable and durable collet or pusher but with indifferent success. The difficulty with the spring fingers of these devices has always been that they crack and fracture or break off or bend 20 where they join the body so that the life of the device is comparatively short requiring frequent replacements.

The usual and common way of making these devices is either to bore out a solid bar into 25 round tubular form and then slit it to form the fingers or to take a tubular bar and slot it to form the spring fingers but the difficulty has been to give the fingers just sufficient flexibility or spring properly to conform to the 30 work, and yet prevent the cracking or fracturing of those fingers at the bases thereof, and the problem has been a difficult one owing to the fact that the fingers have a cross sectional curved form so that the strain thereon 35 is different at different points. Thus as the fingers are arc shaped and, therefore, necessarily curved or convex transversely of their length at the juncture points thereof with the body of the collet or pusher, because the 40 device is necessarily bored cylindrically, the

strain all comes at the corners of each finger,—so that there are thus two forces working against each other, a compression and an expansion, trying to tear the finger apart from its base or body. In other words, in this 55 arc or curved form of finger the strain is acting to compress the finger at the height of the curve or midway between the side edges of the finger, while tending to expand or stretch it beyond its elastic limit at the outer 60 corners of the finger adjacent to the slots, and these two forces working in opposition quickly cause the fracture or cracking and consequent breaking of the finger at the juncture point thereof with its body. In short, it 65 has been found impossible to make a satisfactory long-lived article of this kind with spring fingers having proper flexibility when the fingers are arc-shaped, no matter how the device is heat-treated, since the fingers, being 70 curved transversely, have comparatively little flexibility or spring and, therefore, quickly fracture and break.

Various methods of heat treatment have 75 been tried to prevent this, without success, which, together with the cost of making the collet or pusher, has made them highly expensive due to the frequent renewals necessary.

Therefore, the object of the present improvement is to overcome these difficulties by 80 eliminating the cause for the cracking and fracturing of the fingers and thus provide a collet or pusher in which the fingers have all the flexibility necessary so that the device 85 will stand up better and hence be stronger and longer-lived. Practical tests have shown that the present improvement overcomes, to a large extent, the difficulties referred to.

In the present improvement a tubular bar 90 either formed from a solid bar or originally formed tubular is provided with a series of slots some of which terminate at the outer or front end of the device while the others terminate short of such end thereof, so that the latter are suitably connected by segmentally 95 shaped solid portions like the inner ends of the fingers which prevents too great flexibility of the fingers and consequently pre- 100

vents the breaking off or cracking of the fingers at the inner or base ends thereof.

A device without the combination of slots herein shown and having only the short slots 5 and not the longer slots would be an impracticable one or one having comparatively short life since such a device would have to depend entirely upon the flexibility of the invent fingers with the result that with these 10 short slots all closed at both ends, it follows that when the fingers expanded they would lengthen out and consequently when they reached their elastic limit would have a tendency to fracture or snap off, whereas in the 15 present improvement, when the fingers reach their elastic limit, the fracturing or snapping off of the fingers is prevented by reason of the fact that the split ends of the device can give equally and uniformly around the stock bar 20 and thus should the fingers be expanded up to or beyond their elastic limit the fracturing or snapping off of the fingers either at their base ends or front ends is prevented by the yielding of the split segmental portions 25 at the front of the device, so that the elastic limit of the fingers can be less than heretofore found necessary and yet the device has equally as great or greater flexibility than heretofore with the result that the fingers 30 need not be so resilient as heretofore so that a better and firmer hold on the stock bar is the result with less likelihood of slipping.

In the drawings accompanying and forming a part of this specification—

35 Fig. 1 is a side view of this improved collet or pusher;

Fig. 2 is a longitudinal sectional view thereof;

Fig. 3 is a cross section thereof taken on the 40 line 3—3 of Fig. 1;

Fig. 4 is a rear end view thereof;

Fig. 5 is a cross sectional view taken on the line 5—5 of Fig. 1; and

Fig. 6 is a front end view of the device.

45 Similar characters of reference indicate corresponding parts in the several views.

Before explaining in detail the present improvement and mode of operation thereof, I desire to have it understood that the invention 50 is not limited to the details of construction and arrangement of parts which are illustrated in the accompanying drawings, since the invention is capable of other embodiments, and that the phraseology which I employ is for the purpose of description and not of limitation.

This improved collet or pusher comprises a hollow or tubular member 2 consisting of a body portion 3 terminating in a shoulder 4 60 and a threaded end 5 and a series of resilient fingers 6 spaced lengthwise from each other. These fingers are formed by slotting the tubular member lengthwise different pre-determined distances.

65 In the present instance the device is shown

provided with a pair of long slots 7 opening at the front end of the collet or pusher and intermediate these long slots are shorter slots 8, the front ends of which intermediate slots are joined together by segmental walls 9 substantially similar to the body portion 10. The result of this construction is that while all of the slots are segmentally joined at the body portion only some of them are so joined at the free end of the pusher. The device 70 may have a different or a greater number of free ended slots 7 but in all cases it will have between these longer slots one or more shorter slots 8, both ends of which terminate in a segmentally shaped wall. One of the advantages of this construction is that by varying the length of the shorter slots greater or less resiliency may be given to the fingers according to the character of the work. Thus all 75 of the fingers between the longer slots always terminate in segmentally shaped walls 9 and these walls materially resist too great a flexibility of the fingers at the base thereof and prevent the difficulties hereinbefore referred to.

In the present instance the structure is shown with two spaced segmentally shaped walls 9 at the free end of the collet or pusher each connecting three fingers 6 together, and these walls resist a too great flexibility of the fingers and thus prevent the cracking or breaking of the fingers at their base ends. The number of these segmental walls may be less or greater according to the number of the longer slots provided but in all instances there 80 will be at least two segmentally shaped walls at the outer ends of the fingers so that at least a plurality of the fingers will be joined at their outer ends in the same manner that they are joined at their inner or base ends.

85 The fingers intermediate these segmentally shaped or joining walls 9 and 10 are longitudinally bent the required amount toward the axis of the collet, as at 11, to form work or stock bar engaging faces on the inner sides thereof for effectively gripping the work.

90 Practical tests have proven that this improved device is a very superior one and highly satisfactory as it has just the right amount of flexibility to accomplish the purpose but not sufficient to cause the breakage or fracture of the fingers at the base thereof.

95 These tests under working conditions have disclosed that the segmental joining walls 9 at the front ends of the collet together with the long slots give considerable flexibility to the fingers and yet resist the opposing strains at the base of the fingers for it is obvious that in the form of device shown the strain would have to be sufficient to break off or fracture or bend at least three of the fingers, the joining segmental wall 9 resisting any one finger fracturing or bending independently of another one. After the device is thus made it is 100

suitably heat treated to properly harden and temper the fingers.

The width of the joining wall 9 may be varied thereby changing the length of the shorter slots, thus either decreasing or increasing the flexibility of the fingers, which, as before stated, is a very material advantage, while by having less than all of the slots so joined at their front ends greater flexibility of the fingers is obtained in that the flexibility of the longitudinally bent fingers is also increased without danger of fracturing or bending the same at bases thereof, with the resultant advantage of enabling the device to be inexpensively made in a simple and expeditious manner and without any of the defects of prior devices.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A collet or pusher comprising a hollow member having a plurality of slots opening at the forward end thereof and therebetween a plurality of spaced resilient fingers joined together at the forward end by a solid wall with the fingers bent inwardly toward the axis.

2. A collet or pusher comprising a hollow member having a plurality of slots opening at the forward end thereof and therebetween a plurality of spaced resilient fingers joined together at the forward end by a solid segmental wall with the fingers converging inwardly from both ends thereof toward the axis.

3. A collet or pusher comprising a hollow member having a plurality of slots of different lengths, forming spaced fingers longitudinally bent inward toward the axis to impart flexibility thereto, all of said slots joined at the body of the device and some only thereof joined at the forward end thereby to increase the flexibility of the fingers.

4. A collet or pusher comprising a hollow member having a plurality of slots of different lengths, forming spaced fingers longitudinally bent inward toward the axis to impart flexibility thereto, all of said slots joined at the body of the device and all but a plurality thereof joined at the forward end by segmentally shaped solid walls thereby to increase the flexibility of the fingers.

5. A collet or pusher comprising a hollow member having a plurality of slots of different lengths, forming spaced fingers longitudinally bent inward toward the axis to impart flexibility thereto, all of said slots joined at

the body of the device and all but a plurality thereof joined at the forward end by segmentally shaped solid walls thereby to increase the flexibility of the fingers, said wall having a width substantially corresponding to the body of the device.

6. A hollow collet or pusher having a series of resilient spaced fingers all joined at their base ends and separated at their front ends to form at least two independent front unconnected sets of connected fingers, each of said fingers being bent inwardly toward the axis of the device thereby to yield with the joined together sets of fingers.

Signed at room 1822 Park Row Building, 80 city, county and State of New York, this 12th day of March, 1930.
